UNITED STATES PATENT OFFICE.

EDGAR R. BEACH, OF PHILADELPHIA, PENNSYLVANIA.

DESIGN FOR GAS-BURNER.

Specification forming part of Design No. 6,971, dated November 4, 1873; application filed October 21, 1873.
[Term of Patent 3½ years.]

To all whom it may concern:

Be it known that I, EDGAR R. BEACH, of Philadelphia, in the county of Philadelphia and State of Pennsylvania, have invented a certain new and useful Design for Gas-Burners; and I do hereby declare the following to be a full, clear, and exact description of the invention, such as will enable others skilled in the art to which it pertains to make and use it, reference being had to the accompanying drawings, which form part of this specification, in which—

Figure 1 is a front view, and Fig. 2 is a side view, of my design.

My design for a gas-burner consists of a crescent, mounted upon a flower, the horns of

the crescent being turned down so as to permit the back or periphery to be suitably perforated for the emission of gas, and the flower serving as a standard for attachment to the fixture.

What I claim as my invention, and desire to secure by Letters Patent, is—

The design for a gas-burner, illustrated in the accompanying drawing, consisting of a crescent mounted upon a flower.

In testimony that I claim the foregoing I have hereunto set my hand this 15th day of October, 1873.

Witnesses: EDGAR R. BEACH.
